SURGICAL SUCTION AND PRESSURE APPARATUS

Filed May 5, 1927

Inventor:
By Charles J. Pilling,
A. T. Groves
Attorney.

UNITED STATES PATENT OFFICE

CHARLES J. PILLING, OF LANSDOWNE, PENNSYLVANIA, ASSIGNOR TO THE GEORGE P. PILLING & SON COMPANY, OF PHILADELPHIA, PENNSYLVANIA, A CORPORATION OF PENNSYLVANIA

SURGICAL SUCTION AND PRESSURE APPARATUS

Application filed May 5, 1927. Serial No. 188,944.

This invention relates to improvement in surgical suction and pressure apparatus for providing negative pressure for suction for drawing fluids from the body, for providing pressure for sprays and for vaporizing ether.

Apparatus of this character includes a bottle for containing the liquid to be atomized or sprayed when the apparatus is operated as a pressure device, and for receiving the liquid when the apparatus is used as a suction device, and, in each instance, the bottle is provided with a removable cover having an inlet tube and an outlet tube extending therethrough.

15 An object of my present invention is to provide a novel, simple and efficient means for holding the bottle in a fixed position which will permit the bottle to be easily and quickly removed and replaced or another substituted for it for filling or emptying purposes. Another object is to provide a novel and advantageous clamping means which, at one operation, will clamp the cover upon the bottle and clamp the bottle upon its support, 20 and, at another operation, will release the bottle and, at the same time, release the cover thereon for its easy removal therefrom.

The invention consists in the novel construction, combination and arrangement of 30 elements hereinafter described and claimed.

In the accompanying drawings, illustrating the invention,

Figure 1 is a side view of an apparatus embodying my invention.

35 Figure 2 is a vertical section thereof, on line 2—2 of Fig. 1.

Referring to the drawings, 3 designates a supporting base having a post 4 rising fixedly from the central portion thereof.

40 Screwed into the upper end portion of the post 4 is a threaded rod or stem 5 carrying a spider 6 which is provided with radially projecting arms 7 which support a table 8 and which have up turned ends 9 confining the table between them. By turning the spider 6 and its stem 5, the table 8 may be adjusted vertically to different positions. A lock nut 10 is provided upon the stem 5 to 45 be screwed against the top of the post 4 to

lock the stem and table in different positions of adjustment.

The outer portion of the table 8 is provided with an upwardly extending annular flange 11 which surrounds and projects above 55 a yieldable cushion pad 12 of rubber or other material which rests upon the table 8 for receiving and supporting a bottle 13.

The bottle 13 is provided with a cover 14 which rests upon the top of the neck 15 60 thereof. The cover 14 comprises a body portion 16 having a downwardly extending annular flange 17 which surrounds the bottle neck 15 and positions the cover 14 centrally thereon. Extending through the body portion 16 of the cover are inlet and outlet tubes 18 and 19, respectively, which are fixed in the body portion 16. These tubes 18 and 19 may extend down into the bottle any desired distance suitable for the purpose for which 70 the bottle is used.

Within the flange 17 and secured to the body portion 16 of the cover 14 is a yieldable cushion ring 20 of rubber which is seated upon the top of the bottle neck 15 and which 7 surrounds the tubes 18 and 19.

Connected to the post 4 and extending rearwardly from the back thereof is an arm 21 carrying a standard 22 which rises from the rearward end of the arm. The upper end 30 of the standard is provided with a forwardly extending arm 23 the forward end of which supports a vertically-extending tubular guide 24 comprising an upper portion 25 formed integral with the arm 23 and a lower portion 35 26 screwed into the upper portion 25.

The tubular guide 24 is arranged in axial alignment with the bottle 13 and post 4, and a vertically movable rod 27 is slidably contained within the guide 24 and projects below 90 the bottom thereof. The lower end portion of the rod 27 is provided with a head or clamping member 27^a adapted to engage the bottle cover 14 centrally thereof when the rod 27 is lowered.

The upper end of the rod 27 engages a cam 28 formed on a hand operated lever 29. The lever 29 is fulcrumed, at 30, on the upper end portion of the guide 24 which is bifurcated to receive the lever and the cam.

The rod 27 is pressed against the cam 28 by a spring 31 which encircles the rod 27 within the lower portion 26 of the guide 24 and has its upper end bearing against the bottom of a pin 32 which extends transversely through and beyond the rod 27 and beyond the respective sides thereof. The lower end of the spring 31 bears upon an inwardly-extending, annular flange formed on the bottom of the lower portion 26 of the guide 24.

10 The forward end of the lever 29 terminates in a suitable handle by means of which the lever may be moved down from the position shown by dot-and-dash lines in Fig. 1 to the position shown by full lines therein and back again. The contour of the surface of the cam 28 against which the rod 27 bears is such that when the lever 29 is raised to the position shown by dot-and-dash lines in Fig. 1, the cam 28 will permit the spring 31 to raise the rod 27 and clamping member 27^a to the position shown by similar lines in Fig. 1; and that, when the lever 29 is lowered to the position shown by full lines in Fig. 1, the rod 27 and clamping member 27^a will be forced down against the action of the spring 31 to the position shown by similar lines in Fig. 1.

Shoulders or projections 33 and 34 on the lever 29 are provided to engage the upper portion 25 of the guide 24 and limit the up and down movements, respectively of the lever 29.

25 It will now be understood that when the
bottle 13 with its cover 14 thereon is placed
upon the table 8 and the lever 29 is then
moved down to the position shown by full
lines in Fig. 1, the cover 14 will be clamped
upon the bottle 13 and the cover and bottle to-
gether will be firmly clamped between the
40 clamping member 27^a and the table 8, the pad
12 and the ring 20 yielding, as the clamping
member moves to its final clamping posi-
tion, and making a tight joint between the
cover and the bottle and protecting the bottle
45 against breakage. It will be understood also
that when the lever 29 is raised to the position
shown by dot-and-dash lines in Fig. 1, the
bottle 13 and cover 14 will be freed, permit-
50 ting the bottle easily to be removed from the
table and the cover easily to be removed from
the bottle.

The annular flange 11 on the table 8 provides a means for quickly centering the bottle 13 beneath the clamping member 27^a; and the vertical adjustment of the rod 5 and table 8 provides a means for setting the table in the most desired position relatively to the clamping member 27^a for producing the proper pressure of the cover ring 20 upon the bottle 13 for the desired tight joint.

I claim as my invention:

1. In a bottle holder and in combination, a base having a central post rising therefrom, a bottle receiving table supported by the post,

an arm extending from the post, a standard rising from the arm, an arm extending from the standard, a clamping member movably supported by the last named arm, and a hand operated lever fulcrumed on the last named arm and provided with a cam constructed to move the clamping member toward the table to clamp a bottle between them when the lever is operated.

2. In a bottle holder and in combination, a base having a central post rising therefrom, a vertically adjustable stem screwed into the post and extending above the same, a bottle receiving table supported by the stem, an arm extending from the post, a standard rising from the arm, an arm extending from the standard, a clamping member movably supported by the last named arm, and a hand operated lever fulcrumed on the last named arm and provided with a cam constructed to move the clamping member toward the table to clamp a bottle between them when the lever is operated.

3. In a bottle holder and in combination, a base having a central post rising therefrom, a bottle receiving table supported by the post, an arm extending from the post, a standard rising from the arm, an arm extending from the standard, a rod slidably supported by the last named arm above said table and in axial alignment with said post, a clamping member on the lower end of said rod, and means operable to move the rod and the member downwardly to clamp a bottle between the member and the table.

In testimony whereof I affix my signature.
CHARLES J. PILLING.
